(57) CLAIM

The ornamental design for a makeup box, as shown and described.

DESCRIPTION

FIG. 1 is a top, front, left side perspective view showing my new design for a makeup box;

FIG. 2 is a bottom, back, right side perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a top, front, left side perspective view thereof, showing the makeup box in an opened configuration;

FIG. 10 is an enlarged view of the portion of the makeup box encircled in FIG. 1;

FIG. 11 is an enlarged view of the portion of the makeup box encircled in FIG. 1; and,

FIG. 12 is an enlarged view of the portion of the makeup box encircled in FIG. 1.

The dashed broken lines, and the lightened spaces within, shown in the drawings depict portions of the makeup box that form no part of the claimed design. The dot-dash broken lines shown in FIGS. 1 and 10-12 encircle portions of the claimed design that are illustrated in enlargements and form no part of the claimed design.

1 Claim, 12 Drawing Sheets
